ATTORNEY

UNITED STATES PATENT OFFICE.

WILLIAM P. HARMON, OF SPRINGVILLE, CALIFORNIA.

CORN-HEADER.

1,358,202.

Specification of Letters Patent. Patented Nov. 9, 1920.

Application filed December 13, 1919. Serial No. 344,644.

To all whom it may concern:

Be it known that I, WILLIAM P. HARMON, a citizen of the United States, residing at Springville, county of Tulare, State of California, have invented certain new and useful Improvements in Corn-Headers; and I do declare the following to be a full, clear, and exact description of the same, reference being had to the accompanying drawings, and to the characters of reference marked thereon, which form a part of this application.

This invention relates to improvements in corn headers, the principal object of the invention being to devise an article adapted to be secured to the hand of the user, and by means of which an ear of corn of any kind may be readily cut from the stalk, while allowing the full and free use of the hand to grasp the ear being cut.

Another object is to construct the header in such a way as to remove all strain off the hand and fingers, so that it may be used for indefinite periods at a stretch without unduly tiring the hand or cramping the fingers.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a perspective view of my improved corn header, showing the same, attached to a hand, the latter being in the act of grasping an ear of corn about to be cut or headed.

Fig. 2 is a side elevation of the header.

Referring now more particularly to the characters of reference on the drawings, the numeral 1 denotes a wide band, preferably of leather, and having straps 2 extending from one end adapted to be fastened to buckle catches 3 secured in alinement with the straps on the outside and at the other end of the band.

This band is adapted to be fastened about the wrist of the user, the upper edge being curvally cut away somewhat as at "A," at a point adjacent the beginning of the straps, which point is under the bulge of the thumb 4 of the hand 5, which prevents chafing of the same.

Rigidly fastened to the band 1 outside the same and above the buckles 2 is the heading or cutting member 6. The body 7 of the same, where it connects with the band is convexly curved somewhat, to conform more or less to the curvature of the hand adjacent the little finger 5^a.

A suitable distance above the band the cutting member bends downwardly as at 8, 65 and forms an acute angled V with the body 7, as at 9, the sides of this angle being sharpened to form cutting edges 10.

The bend of the cutting member is substantially in the same plane as the body 70 thereof, and in the direction of the cut-away portion "A" of the band, when the same is laid out flat, or when the band is fastened around the wrist, in a plane substantially at right angles to the hand at the little finger 75 end of the same.

A leather loop 11 is secured to the cutter 6 adjacent the top edge and on the inner surface thereof, being adapted to receive the little finger 5^a therein, and so angled relative to the cutter that the finger will readily slip therein when the hand is in a semi-closed or relaxed position as shown in Fig. 1, as would be the case when grasping an ear of corn therewith.

These headers will preferably be made and sold in pairs, one right and one left hand, so that one may be used on either hand.

With my improved header therefore, the ear to be cut may be loosely grasped, while 90 the cutter is given a quick downward motion, the sharp edged V portion engaging the stalk and severing the same at an angle.

The fact that the same hand on which the header is secured is free to grasp the corn prevents the latter from falling to the ground, and also enables a cutter to be similarly strapped onto the other hand, thus doubling the amount of work one man may do, with little if any increase in actual 100 physical work.

By reason of the fact that the cutter retaining band is secured to the wrist rather than the hand, all the strain of cutting is taken by the wrist and arm, thus permitting the hand to function normally without tiring or cramping the same.

I have found from experience that the person wearing these cutters can cut from one to six heads or ears of corn at one time.

From the foregoing description it will be readily seen that I have produced such

a device as substantially fulfils the object of the invention as set forth herein.

While this specification sets forth in detail the present and preferred construction 5 of the device, still in practice such deviations from such detail may be resorted to as do not form a departure from the spirit of the invention as defined by the appended claims.

10 Having thus described my invention what I claim as new and useful and desire to secure by Letters Patent is:—

15 1. A corn header comprising a flexible band adapted to be strapped around the wrist of the user, and a rigid cutting member secured to the band and projecting upwardly therefrom at right angles to the hand and positioned adjacent the little finger, and being removably secured there- 20 to, whereby the cutting member is held rigidly by the hand while the latter is unobstructed and free to grasp an ear of corn being cut.

25 2. A corn header comprising a flexible band adapted to be strapped around the wrist of the user, and a rigid cutting member secured to the band, and projecting up-

ward therefrom and substantially at right angles thereto, but parallel to the hand, and provided with an inverted V-shaped cutting edge extending away from the plane of the hand, said cutting edge being below the fingers, whereby they are free to grasp an ear of corn above the plane of the knife. 30

3. A corn header comprising a flexible 35 band adapted to be strapped around the wrist of the user, a rigid cutting member projecting upward from the band and secured thereto and positioned substantially at right angles to the hand but parallel 40 thereto adjacent the little finger thereof, an inverted V-shaped cutting portion on said cutter at the top thereof and extending away from the plane of the hand and a flexible loop secured to the upper and 45 inner edge of the cutter and adapted to receive the little finger therein when the fingers are in semi-closed posture.

In testimony whereof I affix my signature in presence of two witnesses.

WILLIAM P. HARMON.
